UNITED STATES PATENT OFFICE.

JOHN D. CHAPMAN, OF RICHWOOD, WEST VIRGINIA.

MACHINE FOR SPRAYING LEATHER.

Application filed April 15, 1922. Serial No. 553,236.

To all whom it may concern:

Be it known that I, JOHN D. CHAPMAN, a citizen of the United States, residing at Richwood, in the county of Nicholas and

5 State of West Virginia, have invented certain new and useful Improvements in Machines for Spraying Leather, of which the following is a specification, reference being had to the accompanying drawings.

10 This invention relates to the art of sponging and washing hides, sides of leather, and other like articles and applying washing compounds thereto, and particularly to a machine whereby this operation may be performed.

15 In the present methods of washing hides and sides of leather, etc., a great deal of liquid used in treating the leather is spilled and wasted, and furthermore the operator 20 gets his clothes soiled and is more or less drenched with the liquid used for treating the leather.

The general object of the present invention is to overcome this difficulty by providing a machine for this purpose which will save both labor and material, the machine being so constructed that one man can operate the machine and do the work of twelve men operating in the ordinary manner and saving material, in that very little 30 of the liquid is spilled.

A further object is to provide a machine of this character in which a spraying device is used and endless belts are provided which 35 carry the leather beneath the spraying device so that all that is necessary to do is to feed the sides of leather or the hides onto the machine, which are carried automatically beneath the spraying device and then 40 discharged automatically upon a truck or other receptacle.

Still another object is to provide an endless conveyor for this purpose consisting of a plurality of chains, each of these chains 45 carrying supports for the leather, which are adapted to lift up one margin of the side or hide off of the supports on which they are initially placed and permit the hide or side to slip down on the supports and be carried 50 by the endless chains, the supports then turning so as to discharge the hides onto a truck.

Another object is to provide a tank disposed beneath the conveyor upon which the 55 liquid from the hides drains, and provide a pump taking liquid from this tank and dis-

charging it to a sprayer to thereby prevent any waste of liquid.

Other objects will appear in the course of the following description.

60 My invention is illustrated in the accompanying drawings, wherein:

Figure 1 is a top plan view of a leather treating machine constructed in accordance 65 with my invention;

Figure 2 is a front elevation of the machine shown in Figure 1;

Figure 3 is an end elevation;

Figure 4 is a transverse section of the machine;

Figure 5 is a top plan view of a portion 70 of the endless chain showing the fingers;

Figure 6 is a side elevation of the construction shown in Figure 5;

Figure 7 is a fragmentary section on the 75 same plane as Figure 4, but showing the position of a finger as it turns from the lower to the upper flight.

Referring to these drawings, it will be seen that my machine comprises a frame 80 consisting of the vertical members 10 suitably braced by braces 11 and by transverse sills 12 at the upper end of the frame, these sills being connected at one end by a longitudinal brace 13. Mounted upon a supporting frame 14, which in turn is mounted upon the main frame below the level of the beams 12, is a transverse shaft 15 carrying upon it a plurality of sprocket wheels 16. At the front of the machine a bracket 17 is 90 mounted, carrying upon it a transverse shaft 18, in turn carrying a plurality of sprocket wheels 19. The shaft 15 is driven by means of a gear wheel 20, in turn driven by a pinion 21 on a shaft 22, this shaft carrying a band wheel 23 whereby the shaft may be driven from any source of power, and a pulley 25.

100 Mounted upon the lower portion of the frame is a tank 26, and also mounted upon the lower portion of the frame is a centrifugal pump 27 whose shaft 28 carries a band wheel 29 driven by a band 30 from the pulley 25. This pump has an intake pipe 31 which extends into the tank 26 and takes 105 liquid therefrom through a perforated head constituting a screen and designated 32. From the pump extends a delivery pipe 33 which extends upward and then extends longitudinally across the top of the frame, 110 as at 34. This portion 34 of the pipe is perforated on its under face, as at 35, so as

to cause liquid to be discharged in streams or in the form of a spray downward upon the hide or side of leather.

Designed to operate over the sprocket 5 wheels 16 and 19 are the endless chains 36 illustrated in detail in Figure 6. These endless chains are sprocket chains and at intervals there are provided links 37 which extend upward to form parallel ears, and 10 pivoted between these ears are the fingers 38 which extend longitudinally of the chain and parallel to the upper flight of the chain. These fingers 38 have downward projections 39 which are so formed as to extend through 15 a link of the chain. The opposite edge faces of the fingers are formed with upwardly and forwardly extending stops 40 having enlargements 41 at their extremities. The fingers are urged into a position parallel 20 to the chain by means of springs 42 which extend around the pintle 43 of each finger and arch over the rear portion of the finger. At intervals in the length of the chain and between each pair of fingers, and 25 preferably disposed adjacent the end of each finger, is a link 44 having an upwardly and rearwardly extending spike or prong 45. In order to keep the chain taut, I provide a longitudinally extending shaft 30 46 mounted in a sliding bearing 47, this bearing being mounted between vertical guides 48, each bearing being urged downward by a spring 49. Mounted upon this shaft 46 are a plurality of sprocket wheels 35 50 coacting with the several chains 36 and intermeshing with said chain and acting as chain tighteners in an obvious manner.

Extending downward from the longitudinally extending beam 13 are downwardly 40 and forwardly extending guides in the form of slats and designated 51, each of these guides or slats having an upwardly and forwardly projecting pin 52. It will be seen that the chains 36 are so disposed that 45 the fingers 38 pass between two of the slats in the course of their travel.

In the operation of this mechanism, the machine is driven by power communicated to the pulley 23, which causes the pump to 50 withdraw liquid from the tank 26 and discharge it through the perforated pipe 34. The side of leather which is to be treated with the compound is placed on the guides 51 and rests upon the pins 52. The side 55 of leather is held in this position until the series of fingers 38 lift it clear of these pins. The side of leather slides down on these fingers until it strikes the stops or hook-shaped members 40. The side of 60 leather is then carried toward the front of the machine beneath the spray of compound from pipe 34 and when it reaches the front of the machine and after passing through the spray, the fingers turn over and deposit the side of leather onto a truck with

the sprayed side down, the hooks 40 holding the leather until it is deposited upon the truck. The spikes or prongs 45 act to prevent the leather from slipping on the conveyor chains as it travels. The springs 70 42 hold the fingers up when they are returning with the lower flight of the endless chains. A shield 53 extends downward from the beam 13 and forward into the tank so as to prevent the operator from being splashed with liquid and so as to drain all surplus liquid back into the tank. Of course, this machine may be used for treating hides by using salt water in the tank 26, and different compounds are to be used 80 for treating different leathers.

It will be seen that in the operation of this device, the fingers travel approximately parallel to the under flight of the chain until they reach the sprocket wheel 16. As each finger reaches this sprocket wheel, the projecting portion 39 of the finger is engaged by the tooth which turns the finger to the position shown in Figure 7, that is at an angle to the chain. The finger as it rises between the guides 51 lifts the lower margin of leather beyond the pins 52 and the leather slides down upon the corresponding fingers of the several chains until the leather strikes the hooks 40 which constitute stops. The leather then travels along and with the chains being held from movement by the prongs 45, until the fingers pass over the front sprocket wheels 19. As the fingers reach the front sprocket wheels, the sprocket teeth will engage the projections 39 on the corresponding fingers and will tip the fingers outward or into angular relation to the chain. The hooks, 90 however, will engage the leather so that the leather will not slip off until the finger has become almost overturned, when the leather will slip off and onto the truck provided for that purpose. It will thus be seen that the hide or side of leather does not have to be touched from the time it is placed upon the guides 51 until it is removed from the truck.

While I have illustrated a construction 105 which has been found thoroughly effective in practice, I do not wish to be limited thereto, as it is obvious that many changes might be made in the details without departing from the spirit of the invention.

I claim:

1. A machine of the character described including a supporting frame, a series of conveyor chains mounted upon the frame and traveling from front to rear thereof, means for driving the chains, and rearwardly directed fingers for supporting the leather normally extending parallel to and resting upon the upper flight of the chains, said fingers being pivoted to the chains, whereby the fingers may turn over from a 115 120 125 130

position parallel to the chains to a position at an angle thereto as the fingers pass from the upper to the lower flights of the chains.

2. A machine of the character described including a supporting frame, a series of conveyor chains mounted upon the frame and traveling from front to rear thereof, means for driving the chains, rearwardly directed fingers normally extending parallel to and resting upon the upper flight of the chains, said fingers being pivoted to the chains for limited movement into angular relation to the lower flight of the chain, whereby said fingers may turn over from a position parallel to the upper flight of the chains to a position at an angle thereto as the fingers pass from the upper to the lower flight of the chains; and means for causing the fingers to be directed rearwardly at an angle to the chains as the fingers pass from the lower to the upper flight of the chains.
3. A machine of the character described including a supporting frame, a series of conveyor chains mounted upon the frame and traveling from front to rear thereof, means for driving the chains, rearwardly directed fingers normally extending parallel to and resting upon the upper flight of the chains, said fingers being pivoted to the chains for limited movement into angular relation to the lower flight of the chain, whereby said fingers may turn over from a position parallel to the upper flight of the chains to a position at an angle thereto as the fingers pass from the upper to the lower flight of the chains, means for causing the fingers to be directed rearwardly at an angle to the chains as the fingers pass from the lower to the upper flight of the chains, and guides extending downward adjacent to the path of movement of the fingers as they pass from the lower to the upper flight of the chains, the fingers passing between said guides.

4. A machine of the character described comprising a supporting frame, a plurality of endless chains, a plurality of pairs of sprocket wheels upon which the chains are mounted, means for driving the sprocket wheels, a series of fingers pivoted at intervals upon each chain and extending in the same direction, means yieldingly holding the fingers in a position parallel to the chain and extending in a direction reverse to the direction of travel of the chain, a series of guides extending downward and forward from the top of the frame and between which guides said fingers pass as they move from the under flight of the chain to the upper flight thereof, each of said guides having pins extending upward therefrom to support the edge of the leather, and means for keeping all of said chains taut.

5. A machine of the character described comprising a supporting frame, a plurality of endless chains, a plurality of pairs of

sprocket wheels upon which the chains are mounted, means for driving the sprocket wheels, a series of fingers pivoted at intervals upon each chain and extending in the same direction, means yieldingly holding the fingers into a position parallel to the chain and extending in a direction reverse to the direction of travel of the chain, each of said fingers having an upwardly and rearwardly projecting hook, a series of guides extending downward and forward from the top of the frame and between which guides said fingers pass as they move from the under flight of the chain to the upper flight thereof, each of said guides having pins extending upward therefrom to support the edge of the leather, and means for keeping all of said chains taut.

6. A machine of the character described comprising a supporting frame, a plurality of endless chains, a plurality of pairs of sprocket wheels upon which the chains are mounted, means for driving the sprocket wheels, a series of fingers pivoted at intervals upon each chain and extending in the same direction, means yieldingly holding the fingers into a position parallel to the chain and extending in a direction reverse to the direction of travel of the chain, each of said fingers having a portion projecting through an adjacent link of the chain and adapted to be engaged and lifted by the teeth of a sprocket wheel into angular relation to the chain and each of said fingers on its opposite edge face being provided with a rearwardly projecting hook.

7. A machine of the character described comprising a supporting frame, a tank mounted upon the base of the frame, parallel shafts mounted upon the frame above the tank, one of said shafts being in advance of the frame, a plurality of sprocket wheels carried upon each of said shafts, endless chains passing over said sprocket wheels, an intermediate shaft mounted in vertically movable bearings and having sprocket wheels engaging the links of said endless chains, springs urging said last named shaft downward, a series of leather supporting fingers pivoted at intervals to each chain and normally extending parallel thereto and rearward with relation to the movement of the chain, springs yieldingly holding the fingers parallel to the chains, means at the rear of the frame for discharging the leather onto said fingers, a spray pipe mounted upon the upper portion of the frame and discharging downward toward said chains, a pump taking liquid from the tank and discharging it into the spray pipe, and means for driving the chains and the pump.

8. A leather treating mechanism of the character described comprising a supporting frame, a spray pipe mounted upon the frame

and discharging downward, a series of endless sprocket chains carried upon the frame below the spray pipe, a transverse shaft mounted on the rear of the frame and carrying sprocket wheels engaging said chains, a transverse shaft carried upon the frame forward of the front thereof and carrying sprocket wheels engaging the chain, certain of the links of each chain having outwardly projecting ears, a series of fingers pivoted to said ears and extending rearward with relation to the direction of movement of the chain and normally extending parallel thereto, each of said fingers having a projection extending through an adjacent link of the chain and adapted to be engaged by the teeth of said sprocket wheel to thereby lift the fingers, springs resisting any lifting of the fingers and yieldingly urging them parallel to the chain, each of said fingers opposite said projecting portion having a hook, a plurality of downwardly and forwardly extending guides attached to the rear of the table and between which guides the fingers pass, pins outwardly projecting from the guides, and means for supplying liquid to the spray pipe and driving said sprocket wheels.

9. In a machine for treating leather, a series of endless conveyors, a series of guides

discharging onto the endless conveyors and having means for impeding the descent of leather over said guides, means carried by the endless conveyors for lifting the lower margin of the leather off of said guides and beyond said impeding means and onto said conveyors, and means for overturning the leather and discharging the leather from the conveyor at one termination of the upper flight of the conveyors.

10. In a machine of the character described, a spray pipe, a series of endless conveyors passing beneath the spray pipe, a series of guides discharging onto the endless conveyors each guide having an upwardly extending member preventing the descent of leather from said guides, means carried by the endless conveyors for lifting the lower margin of the leather off of said guides, above said means and onto the endless chains, means for overturning the leather after it has passed the spray pipe and discharging the leather from the endless chains, a tank disposed below the endless conveyors, and a pump connected to the tank and discharging into said spray pipe.

In testimony whereof I hereunto affix my signature.

JOHN D. CHAPMAN.
